TREAD-GRATING UNIT

Ernest C. Liskey, Jr., Severna Park, Md.

Application November 20, 1957, Serial No. 48,556

Term of patent 14 years

(Cl. D13—1)

Figure 1 is a perspective view of a tread-grating unit showing my new design; and

Figure 2 is an end elevation thereof.

The sides and end of the unit not shown are like the sides and end of the unit which is shown.

The characteristic features of my ornamental design for the grating unit disclosed reside in the group of ribbed portions in spaced relation with the openings and the continuous plain bars or beams, all as shown.

I claim:

The ornamental design for a tread-grating unit, as shown and described.
